CORDED TAPE FOR SLIDE FASTENERS AND
THE LIKEJames A. Hendley, Middletown, Conn., assignor
to The Russell Manufacturing Company, Mid-
dletown, Conn., a corporation

Application January 14, 1935, Serial No. 1,670

1 Claim. (Cl. 139—384)

This invention relates to an improvement in woven, knitted, braided, or otherwise fabricated tapes, and particularly to tapes having corded edges for mounting slide fasteners or the like.

5 So-called "slide fasteners", employed for fastening articles of wearing apparel, such as for instance, as jackets, coats, sweaters, etc., are usually mounted upon tapes, and such tapes, after the mounting of the slide fasteners, have been sewn or otherwise secured to the abutting edges of a garment. Ordinarily, tapes, though initially straight, smooth and flat, become distorted and wrinkled by the application of the slide fasteners thereto and hence impart an unsightly appearance to the garment or other article to which such tapes may be applied.

The distortion of tapes resulting from the application of the fasteners to one edge thereof, as above described, will often effect the curving of 10 the tape in a direction away from the edge upon which the said fasteners are applied, and when sewn to the normally-straight edge of a garment, the tape will reassert itself, to some appreciable degree at least, and not only again distort itself 15 but correspondingly distort and wrinkle the edge of the garment to which it is secured.

It is the main object of the present invention to provide a superior so-called "corded-edge" tape which will not objectionably distort when slide 20 fasteners or the like are attached to its edge.

A further object is to provide a corded-edge tape equipped with slide fasteners which will be relatively free from wrinkles, pockers, and the like, and thus adapt itself for uniform application to a garment.

With the above and other objects in view, as will appear to those skilled in the art from the following, considered in conjunction with the accompanying drawing and appended claim, the 30 present invention includes all features disclosed therein which are novel over the prior art.

In the accompanying drawing:

Fig. 1 is a broken face view of a concavo-convex corded-edge tape embodying the present 40 invention;

Fig. 2 is a transverse sectional view thereof taken on the line 2—2 of Fig. 1;

Fig. 3 is a face view of the tape after the application thereto of the series of spaced clip-like 50 slide fasteners;

Fig. 4 is a transverse sectional view taken on the line 4—4 of Fig. 3; and

Fig. 5 is a broken longitudinal sectional view taken on the line 5—5 of Fig. 3.

55 The tape 10 illustrated in the accompanying

drawing consists of a relatively-thin and flexible body or flap 11 substantially plain along one edge 12 and built up in any approved manner familiar to those skilled in the art to provide a thickened, corded or beaded edge 13 having, for instance, a longitudinally-extending group of strands 14 incorporated therein.

It will be noted by comparison of Figs. 1 and 3 that in Fig. 1 the tape is curved in such manner that its thickened or corded edge 13 constitutes the concave inner or shorter edge of the curved tape, while its relatively-plain opposite edge 12 constitutes the convex outer and longer boundary of the curved tape.

The curved corded-edge tape having the characteristics above referred to may be produced in a variety of ways, such, for instance, as by weaving the corded edge 13 shorter than the opposite edge 12 of the tape.

The desired concavo-convex curved effect may 20 be obtained by forming the corded edge 13 of the tape of strands which are relatively elastic as compared to the strands of the body or flap 11 and particularly those of the edge 12. For instance, ordinary cotton warp strands may be 25 employed for the production of the body or flap 11, while the corded edge 13 may have incorporated therein hard-twisted yarn. Inasmuch as during the weaving operation tension is applied to all of the warps or other longitudinal 30 strands, the hard-twisted yarns will be stretched to a relatively-greater degree than the ordinary strands, and after the weaving is completed and the tape released from restraint, the relatively-elastic hard-twisted strands in the corded edge 13 35 will contract and thus impart the desired curvature to the tape.

Other methods of manufacture are also available, such, for instance, as incorporating in the corded edge 13 strands which have a greater coefficient of shrinkage when wetted or dyed than have the strands in the body or flap-portion 11. Thus, after weaving, the dyeing or other appropriate wetting of the tape will effect a contraction of the strands in the corded edge 13 to a 45 greater degree than in the body or flap 11, and thus impart the desired curvature to the tape. Under this method for the purpose just described, various differentially-shrinkable materials are available, such, for instance, as wool vs. cotton, 50 mercerized cotton vs. unmercerized cotton, etc.

Another mode of manufacture which is worthy of mention consists in weaving in more weft picks adjacent the plain edge 12 than are woven into the fabric at or adjacent the corded edge 55
